UNITED STATES PATENT OFFICE.

ARIBERTO E. CIARLANTE, OF BOSTON, MASSACHUSETTS.

PAPER BOX.

1,122,366.

Specification of Letters Patent. Patented Dec. 29, 1914.

Application filed October 5, 1912. Serial No. 724,043.

To all whom it may concern:

Be it known that I, ARIBERTO E. CIARLANTE, a subject of the King of Italy, residing at Boston, in the county of Suffolk and State of Massachusetts, have invented new and useful Improvements in Paper Boxes, of which the following is a specification.

This invention relates to improvements in paper boxes. More particularly it relates to duplex boxes, the purpose being to provide a box having the advantages of construction and of operation of that herein disclosed, in which a single piece of pasteboard, with its flaps duly fastened, has the appearance and ease of handling, of a single box, when closed, but which really constitutes two boxes. Such a duplex box is convenient for containing two articles that require association together, such as cigarettes and matches; or sedlitz powders of two varieties; or thread in one box and needles, scissors, etc., in the other.

The object of the patent is to protect whatever novelty and utility exists in the construction herein described, the same being illustrated in the accompanying drawings, in which—

Figure 1 is a side elevation showing a box embodying the invention, closed; Fig. 2 is a side elevation of the same, partly opened and in section; Fig. 3 is an end elevation in section on the line 3—3 of Fig. 1; Fig. 4 is a plan of a blank used in making the box; and Fig. 5 is a perspective view of a detail that may be used.

Referring to the drawings the box illustrated is comprised, for the most part, of a single piece of cardboard which is illustrated in Fig. 4. The various parts of this piece are numbered in order that the positions which they assume in the completed box may be readily identified, it being understood that the blank illustrated in Fig. 4 is to be folded on the dotted lines shown in that figure. Thus the part 10 is a front flap of the cover of one of the box portions of the completed article. The adjacent part 11 constitutes the top, 12 the back, and 13 the bottom of this box. 14 which falls to the right in Fig. 2, constitutes the back of the other box portion of the duplex box, 15 its bottom and 16, which falls at the left in Fig. 2, its forward end; it being understood that this flap 16 is long enough to cover

the full height of the double box as illustrated in Fig. 2, although it has been necessary to shorten the representation a little in Fig. 4 in order to conform to the limits of the sheet of drawing. The flaps 11' which are attached to the top 11 constitute the sides of the cover of the upper box; and the flaps 15' similarly constitute the sides of the under box. These have edges 11'' and 15'' respectively which are adapted to register together as shown in Fig. 1, when the flaps 11' and 15' are respectively folded into position, the edges 11'' and 15'' abutting together in the same plane and constituting stops for each other. To this end these edges are cut with oblique edges, that on the flap 11' running from the corner at the hinge 17 down to the level of the bottom 13, whence the flap continues straight beside the edge of the bottom 13; and that of the flap 15' running from the corresponding corner, which is at the outer end of its box, and then continuing in a horizontal direction to the hinge 18 at the level of the top of its box, which is the same as that of the bottom of the upper box. It will be understood that the corners of the flaps 10 and 11' where they come together may be held by stays 19 applied in the usual way; and that the other corners where flaps come together may be so fastened, as indicated by the reference numerals 19, particularly where the flaps 13' which constitute the sides of the upper box are joined to the back 12 of that box and where the sides 15' are joined to the back 14 of the lower box and to the front 16 of the upper box. In place of these stays any other suitable method of fastening the parts together may be employed such as covering the parts with a decorative paper.

The box thus described is complete and is made of one piece with its fastenings. In such a box the part marked 20 in Fig. 2 is absent and also the part marked 21 in the same figure. These are stiffening pieces substantially in the form illustrated in Fig. 5, which shows in detail the shape of the part 21. The part 20 is of similar shape. When the part 20 is present the cover 11 shuts down upon its top and the edge of part 10 shuts down upon the edge of part 14, Fig. 2. When a box so constructed is opened, the right hand portion of the part 20 constitutes the front of the box and

the box opens only at the top; while if the part 20 be absent the box opens at both top and end, which is advantageous for some purposes, such as for cigarette boxes. When 5 the part 21 is present, the bottom 13 shuts down upon its top edge, and thus the lower box is somewhat more definite in its shape when the part 21 is absent; but for many purposes the box may be sufficient without 10 either the part 20 or 21. It will be understood that when the whole box is closed the bottom 13 and its side flaps 13' slip within the side flaps 15' and also within the side flaps 11'. 15 A box made as described presents the simple appearance illustrated in Fig. 1, showing a single crack, between 11'' and 15'', on each side and yet can be opened into two boxes. As illustrated these boxes are 20 of different depths, but it will be understood that the relative dimensions of the parts may be varied. The box may be used with both boxes facing in the same direction, as illustrated in Fig. 2; or it may be 25 considered advantageous to hold cigarettes, for example, in the upper portion of Fig. 2 on top of the part 13 and to fasten matches on the underside of part 13. In such case the user who wishes to get at the matches 30 turns the side 15 up and lifts the part 16, 15; or turns the side 11 up and lifts the part 10, 11, when he wishes to get at the cigarettes.

I claim:

1. A duplex box comprising a box body portion and two covers hinged thereto at diagonally opposite edges, each cover incasing part of the side of the said box body and the two covers together incasing the whole of the sides thereof and seating themselves against each other; that cover which is under the box body being off-set therefrom, thus forming another box.

2. A duplex box including the combination of three elements integrally connected and folded so that one of them intervenes between the other two, which serve as covers to the opposite sides of it; a flap at each edge of each of said elements, the said intervening element being attached at each of its ends to another of said elements through the said flap there located; the flaps on the said intervening element being folded to combine with one of these said cover elements, its flap and its intervening flap to 55 form the box; and the flaps of the other cover element being folded to combine with it and with each other and the said intervening element to form another box.

Signed by me at Boston, Mass., this 1st 60 day of October, 1912.
